UNITED STATES PATENT OFFICE.

GEORGE C. HOLT, OF FORT MADISON, IOWA, ASSIGNOR TO W. A. SHEAFFER PEN CO., OF FORT MADISON, IOWA, A CORPORATION OF IOWA.

DESIGN FOR AN INK BOTTLE.

Application filed April 12, 1926. Serial No. 17,262. Term of patent 14 years.

To all whom it may concern:

Be it known that I, GEORGE C. HOLT, a citizen of the United States, residing at Fort Madison, in the county of Lee and State of Iowa, have invented a new, original, and ornamental Design for an Ink Bottle, of which the following is a specification, reference being had to the accompanying drawing, forming a part thereof.

Figure 1 is a top plan view of an ink bottle showing my new design;

Figure 2 is a side elevational view of the same; and

Figure 3 is a bottom plan view.

I claim:

The ornamental design for an ink bottle substantially as shown.

GEORGE C. HOLT.
